Inventor:

Fredric Engine Drown

UNITED STATES PATENT OFFICE.

FREDERICK EUGENE DROWN, OF PAWTUCKET, RHODE ISLAND.

BLEACHING-KEIR.

SPECIFICATION forming part of Letters Patent No. 415,191, dated November 19, 1889.

Application filed March 19, 1888. Serial No. 267,707. (No model.)

To all whom it may concern:

Be it known that I, FREDERICK EUGENE DROWN, a citizen of the United States, residing at Pawtucket, in the county of Providence and State of Rhode Island, have invented a new and useful apparatus termed a "Bleaching-Keir," for the purpose of bleaching cotton cops, yarns, and fabrics, of which the following is a specification.

10 It is the object of my invention to bleach cotton cops, yarns, and fabrics in bulk, whereby all portions of the material under treatment may be simultaneously acted upon by the treating-liquors.

15 By the use of my bleaching-keir the bleaching of cotton cops, yarns, and fabrics can be very thoroughly effected with great economy of time, labor, chemicals, and heat, simplification and cheapness of the apparatus, and 20 reduction of the space required.

In order that my invention may be more readily understood, I proceed to describe the same with reference to the accompanying drawings, in which—

25 Figure 1 is a vertical section, and Fig. 2 is a horizontal section.

A is a vessel, termed a "keir," inclosing a rotating perforated basket B, fixed to a hollow perforated vertical shaft C.

30 D' D² are the man-holes in keir A.

E is a pipe admitting steam to keir A.

F' F² are pumps which transfer the liquor from bottom of keir A through pipes G' G² H' H² and the gland I and shaft C into basket 35 B, which contains the cotton cops, yarns, or fabrics to be treated.

J' J² are the pipes admitting liquors into shaft C, thence into basket B, thence into keir A.

40 K is a pulley on which the driving-belt is placed for the purpose of rotating basket B.

L' L² L³ L⁴ are valves that control the admittance of liquors to keir A.

45 M' M² are stuffing-boxes in keir A for shaft C.

N' N² are bearings for shaft C.

O' O² are suction-pipes from bottom of keir A to pumps F' F².

P is a vent-pipe in bottom of keir A.

50 Q is a water-glass on keir A.

R is a safety-valve on keir A.

S is a step supporting shaft C.

T is an air-inlet from pressure-blower.

In bleaching I do not confine myself to any

one process or particular steps of operation. 55

The cotton cops, yarns, or fabrics are placed

in basket B, and the ordinary operations in

bleaching them I describe as follows: The

treating-liquors are admitted into keir A

through pipes J' H' or J² H² and circulated 60

through the material to be bleached in bas-

ket B by pumps F' or F², which transfer the

liquor from keir A through pipes G' or G²

H' or H² and the shaft C into basket B. I

have found that the liquor can be discharged 65

into basket B by means of a stationary pipe

arranged to discharge downward into basket

B; but I prefer to use the hollow perforated

shaft C. After treatment the liquor can be

pumped out through pipes J' or J², or run out 70

through vent-pipe P. Steam is admitted to

keir A through pipe E, and air through pipe T.

Having thus described my invention and

the manner of operating it in practice, I claim

as my invention and desire to secure by Let-

ters Patent—

1. In an apparatus for bleaching or dyeing, the combination of the vertical stationary steam-tight vessel A, having in its top tight-closing doors D', with a rotating cylinder B, 80 having perforated sides, and a hollow perforated shaft C, having steam-tight joints with vessel A, substantially as described.

2. In an apparatus for bleaching or dyeing, the combination of the vertical stationary 85 steam-tight vessel A, the interior rotating cylinder B, having perforated sides, and the hollow perforated shaft C, and the pumps F', having pipes connecting with vessel A and shaft C, substantially as described. 90

3. In an apparatus for bleaching or dyeing, the combination of the vertical stationary steam-tight vessel A, having in its top tight-closing doors D', and steam-pipe E and vent-pipe P, with a rotating cylinder B, having 95 perforated sides, and a hollow perforated shaft C, having steam-tight joints with vessel A, substantially as described.

FREDERICK EUGENE DROWN.
